UNITED STATES PATENT OFFICE.

EDWARD E. GOLD, OF NEW YORK, N. Y.

VALVE FOR STEAM-PIPES OF RAILWAY-CARS.

SPECIFICATION forming part of Letters Patent No. 498,545, dated May 30, 1893.

Application filed June 26, 1890. Serial No. 386,864. (No model.)

To all whom it may concern:

Be it known that I, EDWARD E. GOLD, a citizen of the United States, residing in New York city, in the county and State of New York, have invented certain new and useful Improvements in Valves for Steam-Pipes of Railway-Cars, of which the following is a specification.

This invention relates to valves for controlling the main steam pipes or train-pipes of railway cars.

In heating railway cars by steam it is customary to carry the steam from the locomotive boiler through the train by means of what is known as a main steam pipe, or train-pipe. This pipe is made up of successive lengths carried by the successive cars of the train, and connected together between the cars by means of suitable pipe couplings. The length of the main steam pipe on each car is extended sometimes beneath the car floor, and sometimes within the car.

Two radically different systems of piping cars for steam heating exist in the art. According to one, which for convenience I will designate the "loop system," the radiating pipes on each car are connected in a loop which joins the main steam pipe or train-pipe by a compound valve, which in one position connects the loop serially with the train-pipe, so that the steam flows from the latter through the loop and then returns to the train-pipe to continue its flow to the next car in the rear; and in the opposite position cuts the loop out of connection with the train-pipe, so that it is isolated therefrom, and the steam flows directly through the train-pipe. My present invention has no reference to this system, not being applicable thereto. According to the other system, which I will designate the "branch system," the radiating pipes or radiators in each car are in one or more branches which take steam from the main steam pipe or train-pipe, controlled by a throttle valve in each branch. Each branch terminates in some kind of a trap for collecting or discharging the water of condensation that forms in the radiators, discharging this water all externally, (instead of directing more or less of it back into the train-pipe as in the loop system.) It is to this "branch system" of piping for railway-car heating that my invention

alone pertains. In either system it is necessary to supply the length of the main steam pipe on each car with one or more valves in order that when the car is the last one on a train the pipe may be closed off to prevent escape of steam at the open end of the pipe at the rear of the last car. In the "loop system" the same compound valve which connects the loop with the train-pipe has in some constructions its valve-piston, or in other constructions an auxiliary valve-piston, adapted to perform this office of closing off the train-pipe at the rear of the train. It is thus an advantage of the loop system that on each car but one connection need be made with the train-pipe, namely, with the valve-casing of the compound valve, joined into the train-pipe usually at the middle of the car.

In the "branch system" it has heretofore been customary to take off the two or more branches from the train-pipe usually at opposite ends of the car, but sometimes at the middle, by a T or X connection; also to fit the train-pipe at opposite ends of the car with stop-cocks for closing off the end of the pipe at the rear of the train; and also, in the best practice, to fit the train-pipe on each car with one or more condensation chambers or separators for draining off from the train-pipe any water of condensation that may form in it. Accordingly in the "branch system" the train-pipe is ordinarily cut into by several different fittings or connections in the course of its length, a feature wherein this system as heretofore applied has been inferior to the "loop system," although in nearly all other respects possessing important advantages thereto.

It is an important object of my invention to provide a construction applicable to the "branch system" which shall obviate the disadvantage of the application of these several fittings, and provide a single fitting applicable to the train-pipe in their stead, so that in this respect the "branch system" shall be as convenient and simple of application as the "loop system," and shall have the same advantages.

My present invention therefore has for its object an improved construction of train-pipe valve applicable to the piping of railway cars according to the "branch system" of steam-

heating, in place of the two separate stop-cocks heretofore used, and serving also to take the place of the T or X pipe-connections heretofore used for joining the branch pipes.

5 According to my present invention I provide an improved construction of train-pipe valve whereby only one valve is necessary to each ear, being applied preferably in the middle of the train-pipe, and adapted to close off 10 the portion or section of pipe to either side of the valve, or by moving the valve to an intermediate position, to leave the passage unobstructed. The branch pipe or pipes entering the car are connected directly with the casting 15 of the valve.

The valve-casing or shell constitutes a separating chamber for disengaging particles of water or steam, and for catching any sediment. The condensed water is discharged 20 from the valve casing by means of a thermostatic drainage trap, or an automatic relief valve, or preferably by both. The valve proper is manipulated to throw it to either extreme position to close one or other of the 25 pipe sections, or to hold it in the intermediate position to form a free through-and-through passage, by means of a suitable operating handle. Means are provided for locking this handle in either of the three positions. When, 30 as is usual, the train-pipe extends beneath the floor of the car the handle of the valve extends up through the floor, so that the valve may be operated from within the car.

Figure 1 of the accompanying drawings is 35 a vertical longitudinal section through the floor portion of a railway car, showing the main steam pipe or train-pipe, and the connections thereof extending to the radiators in the car. The portions of the car intermediate of its middle and ends are broken out in 40 order to shorten the view. Fig. 2 is a horizontal section through a car cut in a plane close above the floor, and showing in plan the heaters or radiators and the several steam 45 pipes and their connections. The car is broken out in the same manner as Fig. 1, and a portion of the floor is broken away to show the train-pipe valve. Fig. 3 is a vertical transverse section of the valve in its preferred 50 form, cut in the plane of the line 3—3 in Fig. 4. Figs. 4 and 4^a constitute a vertical longitudinal section thereof, cut in the plane of the line 4—4 in Fig. 3, Fig. 4 showing the parts in one position and Fig. 4^a showing them in 55 another position. Fig. 5 is a plan of the slotted floor plate, the lever being in section on the line 5—5 in Fig. 3. Fig. 6 is a vertical longitudinal section of a modified construction of valve. Fig. 7 is a transverse elevation of 60 the valve proper and its operating arm in Fig. 6 removed. Fig. 8 is a vertical longitudinal section of a railway car, showing a different method of applying the train-valve. Fig. 9 is a vertical longitudinal section answering to 65 Fig. 4, but showing a modification wherein the valve is capable of seating at only one side, it being necessary to apply two such valves

to the train-pipe, as shown in Fig. 10. Fig. 10 is a horizontal section in the plane of the axes of the pipes, showing a modified construction of valve. Fig. 11 is a vertical transverse section thereof, cut in the plane of the line 11—11 in Fig. 10.

Referring to Figs. 1 and 2, let A designate the length of the main steam pipe or train-pipe carried by the car, B B the heating coils or radiators within the car, which may be of any suitable kind or construction (heat storage radiators according to the Gold system being shown), C C the branch steam pipes 80 branching from the main pipe and leading to these radiators, and D D the drainage pipes for carrying the water of condensation from the radiators and conducting it beneath the floor of the car to suitable traps shown at E E. 85 These traps are immaterial to my present invention and may be any suitable construction of steam traps, either of the thermostatic order, or the pressure relief order. I prefer the construction of thermostatic trap shown 90 in my Patent No. 424,779, dated April 1, 1890, and of relief trap shown in my Patent No. 472,116, dated April 5, 1892. The ends of the main pipe A are fitted with coupling heads a which are ordinarily connected to them 95 through the medium of a length of flexible hose b.

Ordinarily heretofore in the "branch system" of piping a stop-cock or valve was applied at each end of the pipe A close to its connection with the flexible pipe, as indicated in dotted lines at c c. According to the best practice heretofore I have applied condensation chambers or sediment wells in the position shown in dotted lines at d d, that is near 100 each end of the train-pipe, in order to separate the condensed water and automatically drain it off. According to my present invention I apply, preferably in the middle of the 105 train-pipe, as shown in Figs. 1 and 2, a train-pipe valve, designated as a whole by the letter F. The respective portions or sections of the train-pipe on opposite sides of this valve enter it at openings formed in its casing, preferably in line with one another, and the 110 branch pipes C C enter suitable openings in the sides of the casing, preferably also opposite to, and in line with, one another. The 115 valve-casing thus takes the place of the pipe fittings or T's heretofore employed in the said 120 branch system.

The construction of the valve is best shown in Figs. 3 and 4. Its casing G is preferably in the form of an inverted cone or pyramid, the walls of which slope upwardly from its 125 bottom end, and the respective pipes A and C entering it near its top. The casing is formed with two opposite openings for communication with the two sections of the main pipe A A, the thimbles A' A' being screwed 130 into these openings, and their inner ends forming valve-seats f f. The sections of the main pipe A are connected to these thimbles through coupling unions e, one of which is

shown in Fig. 4. A movable valve or valve proper H is mounted within the casing between the valve seats f f. This valve is constructed at its opposite ends to fit against the opposite seats, being preferably faced with some suitable composition such as a ring g of Jenkins' packing at each end. It is of such length that when standing in the mid position a clear space is left between its opposite faces and the respective seats for the passage of steam from one section of the train-pipe into the valve-casing and out therefrom unobstructedly into the other section of the train-pipe. The valve is preferably made in the form of a short cylinder the axis of which is coincident with the axes of the thimbles A', and which is guided in its movement by being confined between concave faces of guide-bars or slideways J J, formed preferably integrally with the casing G.

In the construction shown in Figs. 3 and 4 the valve H is moved by the arm K of an operating lever, which arm has a rounded end entering a slot formed in the valve. This arm is fixed on a spindle L which passes out through a stuffing-box in one side of the casing, and has fixed on its outer end an arm or lever M which extends thence up through the floor of the car, its upper end forming a handle which may be grasped by a train hand to throw it from one position to another and thereby to move the valve H. When the lever is in its mid position the valve is held midway between the two seats f f so that the steam has free passage around it in flowing through the train-pipe. When the lever is thrown to its extreme position to either side the valve is moved until one face or the other comes against one or the other of the valve seats f. In this position it closes off one or other of the sections of the train-pipe. This is the position only of the valve on the last car of the train, all of the others being in the mid-position. In either position of the valve there is free communication between the chamber or interior of the casing G and the lateral outlets to the branch pipes C C, so that it is impossible by any manipulation of the valve to close off steam from these branches.

The circulation of steam in the branch pipes is controlled, as usual, by means of throttle valves h h applied in the pipes C C within the car. The steam enters through these pipes if their valves be open, and in the construction shown in Figs. 1 and 2, divides at their T fittings i flowing in opposite directions to the opposite ends of the car and enters the radiators B B. At the ends the pipe is carried laterally at C' C' and then back in order to provide for its expansion and contraction. Each pipe then enters the steam space or passage in its radiator B. From each radiator the water of condensation is drawn through a pipe D, the pipes from the two radiators on one side of the car uniting and leading to the drainage trap E beneath the

floor of the car by which the water of condensation is automatically discharged.

The lower portion of the valve-casing G beneath the levels of the pipes A A and C C constitutes a condensation-water chamber and sediment well. The sediment accumulates in the bottom and may be blown out from time to time by unscrewing a plug j. Somewhat above the bottom of the casing, and high enough to avoid the sediment, are two openings designed for the attachment respectively of a thermostatic drainage trap or valve P and an automatic relief valve Q, as shown in Fig. 4. These valves are of any ordinary or suitable construction. The thermostatic trap P is constructed to remain closed so long as a certain temperature is maintained, but whenever water of condensation accumulates in the casing and remains sufficiently long to be cooled to the proper degree, it causes the contraction of a diaphragm or thermo-expansion vessel p away from its seat, thereby permitting the water of condensation to blow out therefrom until the chamber is emptied down to the level of the outlet opening, or until by blowing off steam or hot water through the trap its diaphragm is re-expanded and closes it. The preferred construction of such traps is the one shown in my Patent No. 424,779, dated April 1, 1890. The pressure-relief valve Q is a valve which opens inwardly and is pressed upon by a spring and closed whenever there is a sufficient pressure of steam within the casing. When the steam is turned off from the train, or a car is uncoupled, the escape of pressure causes this valve to open and drain off any water of condensation irrespective of its temperature. By the construction of the valve-casing G as a pendent pocket extending below the level of the pipes, and providing it with a thermostatic trap P and the relief valve or trap Q it is made to take the place of the two condensation chambers and their traps heretofore applied in the positions shown at d d in Fig. 1.

In order to provide further for the rapid blowing out of any condensation water at the end of the train-pipe in order both to maintain a circulation of steam therein and to prevent the accumulation of hot water of condensation, which being hot and under pressure cannot escape through either the thermostatic trap P or the dynamic valve Q, I provide in addition a minute blow-hole or steam escape port k opening into the casing in the path of the valve H where it can be controlled thereby. It is preferably formed through one of the guiding faces of the slideways J J, and exactly in the middle between the two valve-seats f f. The valve H is short enough so that when it is seated against either seat its opposite end uncovers the blow-hole k and permits the continual escape of steam therethrough. This of course occurs only at the valve F on the rear car of the train. This steam carries with it continually more

or less water of condensation, and in case the valve-casing or chamber should fill with condensation water up to or nearly to its level it will carry off all condensed water that may 5 subsequently accumulate. The water of condensation in the pipes is carried by the current of steam toward the end of the pipe, and this blow-hole forms a convenient means for discharging it. The blow-holes of all the 10 valves, except the rear one in the train, are closed by reason of the valve proper, H, being in its mid-position where it covers the blow-hole.

In order to provide against the contingency 15 of accumulated water in the valve-casing failing to be discharged therefrom through derangement of the traps P and Q (a very improbable contingency in case both traps P and Q are used) and of such accumulated water 20 freezing, I prefer to construct the valve-casing of an open-topped casting or shell, closed by an elastic or yielding diaphragm R. By reason of the tapering form of the valve-casing the expansion of the water in freezing 25 is forced to exert itself upwardly by the yielding of this diaphragm and the bursting of the casing is prevented. The diaphragm is preferably fastened down and inclosed and protected by the cast-metal cap G' fastened 30 by screws or otherwise over the top of the casing G.

In order to hold the lever M in either of its three positions means are provided for locking its upper or handle end in place. 35 These means may be variously modified, a simple and suitable construction being that shown in Figs. 3, 4 and 5. A spring arm N is applied to the upper portion of the lever M, its tendency being to spring away from the lever 40 M. Its upper or free end extends adjacent to the handle end of the lever, so that by grasping the latter the spring may be drawn toward it and compressed. This movement releases the spring N from engagement with the teeth 45 on a ratchet-bar T, forming part of the slotted plate t through which the lever works, and which plate may be conveniently screwed or fastened to the floor of the car, under or at the end of one of the seats thereof, where the 50 handle may be conveniently accessible to a person in the aisle. The ratchet-bar T, which is preferably arc-shaped, has teeth or notches which are engaged by opposite pawls or teeth n n formed on the spring N. When the lever M is in its upright or mid-position these pawl projections n are engaged between opposite shoulders l l on the ratchet-bar. In order to throw the lever the spring N is drawn 55 toward it to withdraw the pawls from these shoulders, and it is then thrust to either side until it is stopped by the contact of the valve H with the valve-seat. It is pressed over far enough to force the valve into very tight contact with the valve-seat, and in so doing the rearward of the two pawl projections n clicks 60 over the inclined teeth m of the ratchet-bar, and when the lever is released it is held in

position by the engagement of the pawl with one of these teeth, as shown in dotted lines in Fig. 5. In order to stiffen the spring N 70 against lateral thrust the lever M may be provided with a stud q projecting through a hole in the spring.

The modification shown in Figs. 6 and 7 has a valve proper, H, which is pivoted by means 75 of pivot-screws to the ends of the forks of the lever-arm K, which in this construction is bifurcated. To the valve H is attached a loop-shaped wire spring u, the lower portion of which is engaged between two fingers u' on 80 the lever-arm K. The tension of this spring holds the valve H in a vertical plane and in line with the axis of the lever K when turned to a mid position, but when it is placed against either seat f the spring yields and permits the 85 valve to seat flatwise thereagainst. The thimbles A' are of somewhat different construction, being screwed into the valve-casing G and fastened therein by set-screws v, and the train-pipe sections A A being screwed directly into the thimbles. In other respects 90 this construction is the same as that first described except that the blow-hole k is omitted and the cap or cover of the casing is cast integrally with it, there being no corrugated dia- 95 phragm.

Fig. 8 shows a modified means of applying my improved train pipe valve. Two valves are here applied to the train pipe near the opposite ends of the car. In this case the branch steam pipe C is a short pipe, passing upwardly, provided with a valve h and entering the end of the radiator B or other heater, the piping being more simple than in the arrangement shown in Figs. 1 and 2. When two train pipe 105 valves F are thus employed each valve is movable in use to only two positions, namely the open or mid position, and the position to close off the section of the train pipe extending to the end of the car. The valves need not be 110 set to the position in which they would close off the communication with the middle section of the train pipe extending between the two valves. Consequently the valve need have but one seat and the lever M need be 115 movable to only two positions. A suitable construction for such valves is shown in Fig. 9. The valve shell or casing G is or may be of the same construction as already described. Brass thimbles are screwed into it at opposite 120 sides for the attachment of the sections of the train pipe, but only one of these thimbles A' is formed with a seat f', the other lettered A² being devoid of a valve seat. The valve may be otherwise of the same construction already 125 described, the only difference being that the ratchet bar or plate on the car floor will be constructed to admit of a movement of the lever M from the mid-position to one side only in order to bring the valve against the one 130 seat f'. Instead of having two opposite openings for the attachment of the branch pipes C C, a single opening may be provided, and in case two radiators are to be supplied with

steam the single pipe attached to said opening will be branched to the two radiators. In such case the single opening may be formed through the top of the casing G, as shown in Fig. 9.

- Figs. 10 and 11 show a modified construction of valve wherein the casing is not extended downwardly to form a condensation pocket or sediment well and is unprovided with traps or drainage valves for carrying off water of condensation. This construction of valve is adapted for use on train pipes which are provided with separate sediment wells and traps, as shown in dotted lines at d d Fig. 15. 1. The valve shell or casing G is provided with seats f f at opposite ends in communication with the respective sections of steam pipe A. The valve proper H which is preferably cylindrical moves in guides or ways formed 20 within the casing and is adapted to seat against either of the seats or occupy an intermediate position. In order to provide a free passage for the steam from one section of the pipe to the other when the valve is in 25 the intermediate position, the casing G is formed with passages or ports w w extending along opposite sides, as shown in Fig. 10. The openings for the attachment of the branch pipes C C communicate with these passages. 30 The valve proper H is partly cut away on one side and formed with rack teeth y with which meshes a pinion z fixed on the lower end of the spindle M' which extends hence upwardly through the car floor and bears on 35 its upper end an operating handle or knob M² by which it may be turned to shift the valve. In order to hold the spindle and valve in either position a toothed disk P' may be fixed on the spindle M' and be engaged by 40 the end of a pivoted lever or pawl N' normally pressed into engagement therewith by a spring n' and provided with an upwardly projecting arm N² which may be pressed down by the foot, or otherwise to throw up the pawl N' 45 out of engagement with the disk P' whenever it is desired to operate the valve. In either extreme position of the valve proper H it uncovers one or the other of two blow holes k and k' extending downwardly through the 50 bottom of the casing so that there is an escape of steam from the blow hole thus uncovered at the end of the train.

My invention is not limited to the precise constructions and modes of operation shown 55 and described, but may be variously modified without departing from its essential features.

- I claim as my invention the following-defined novel features and combinations, substantially as hereinbefore described, namely: 60 1. A train-pipe valve for the steam heating system of a railway car, consisting of a valve-casing and a valve movable therein, said casing formed with a cavity or chamber and openings thereinto communicating with the opposite sections of the train-pipe and a branch opening thereinto communicating with the branch steam-pipe leading to the radiator 65

within the car, said branch pipe being permanently in communication with said chamber, and said valve constructed relatively to 70 said casing to close in its extreme position one and only one of said train-pipe openings, whereby to close off the train-pipe at the rear of the train, and in its middle position to afford an unobstructed passage between said 75 openings through said chamber, whereby to permit passage of steam to the car in the rear, and also constructed relatively to said casing to be free from said branch opening and hence incapable of interrupting the communication 80 of said branch pipe with said chamber, whereby in either position of the valve steam may flow from the locomotive boiler through the train-pipe to said chamber and thence into 85 said branch-pipe.

2. A train-pipe valve for the steam heating system of a railway car, consisting of a valve-casing and a valve movable therein, said casing formed with a cavity or chamber and openings thereinto communicating with the opposite sections of the train-pipe and a branch opening thereinto communicating with the branch steam-pipe leading to the radiator within the car, said branch-pipe opening being permanently in communication with said 90 chamber, and said valve movable to three positions and constructed relatively to said casing to close in each of its extreme positions the corresponding one of the two train-pipe openings, whereby to close off the train-pipe at the rear of the train whichever end of the car is turned rearward, and in its middle position to afford an unobstructed passage between said opening through said chamber, whereby to permit passage of steam to 95 the car in the rear, and also constructed relatively to said casing to be free from said branch opening and hence incapable of interrupting the communication of said branch pipe with said chamber, whereby in either 100 position of the valve steam may flow from the locomotive boiler through the train-pipe to said chamber and thence into said branch-pipe.

3. In a car heating system the combination 115 with the main steam pipe, a branch pipe leading therefrom to a radiator in the car, and a throttle-valve in said branch controlling the flow of steam to the radiator, of a valve casing interposed in the main pipe at the junction of said branch pipe, consisting of a shell 120 or chamber having opposite seats with their openings communicating with the respective sections of the main pipe, and an opening communicating with said branch pipe, and a cut-off valve movable in said shell to three 125 different positions, in one of which it is seated against one of said seats to close off one section of the main pipe, in another of which it is seated against the other seat to close the other section, and in the third position it is unseated from both seats to leave free communication through the pipe.

4. A valve for the main steam pipe of a rail-

way car, consisting of a casing having oppositely arranged valve seats and openings therefrom for communication with the respective sections of said pipe, combined with a valve 5 mounted to move within said casing between said valve seats and movable to three different positions, in one of which it is seated against one of said seats to close off one section of the main pipe, in another of which it 10 is seated against the other seat to close the other section, and in the third position it stands intermediate of the seats to leave free communication between them, the valve casing being formed with a free space or passage 15 around the valve when the latter is in the intermediate position, and a branch pipe opening in constant communication with said space or passage, whereby said valve is incapable of closing said passage.

20 5. In a car heating system the combination with the main steam pipe, a branch pipe leading therefrom to a radiator in the car, and a throttle-valve in said branch controlling the flow of steam to the radiator, of a valve interposed in the main pipe at the junction of 25 said branch pipe, consisting of a casing formed with a chamber and openings thereinto communicating with the respective sections of the main pipe, and an opening communicating 30 with said branch pipe, and a sliding valve movable in guides or slideways within said shell, too small to fill said chamber, so that it is incapable of obstructing the communication of said branch-pipe opening therewith, 35 and adapted when in one position to close against a seat and shut off one section of the main pipe, and when in another position to be unseated therefrom and leave free communication between the sections of pipe, and 40 mechanical means for operating said valve from the exterior of the shell.

6. A valve for the main steam pipe of a railway car, consisting of a shell or chamber having opposite valve seats and openings therefrom on the same axis for communication 45 with the respective sections of said pipe, and formed with cylindrical guide ways concentric with said axis, combined with a cylindrical valve movable in said guide ways, 50 adapted in its extreme positions to close against the respective seats, and when in an intermediate position to afford free communication between said seats, and mechanical means for operating said valve from the exterior of the shell.

55 7. A valve for the main steam pipe of a railway car, consisting of a shell or chamber having openings for communication with the respective sections of said pipe, and formed with 60 guides or slide ways, and with a space or passage between said openings beyond said slide ways and exterior to the path of travel of the valve combined with a sliding valve movable in said slide ways adapted when in 65 one extreme position to close one of the openings communicating with the main pipe in

order to close off the pipe at the end of the train, and the valve shell formed with a blow hole through said slide ways and opening exterior to the shell, arranged in position to be 70 normally covered and closed by the valve, but to be uncovered thereby when the valve is in said extreme position, in order that steam may escape through this blow hole from the valve at the end of the train.

75 8. A valve for the main-steam-pipe of a railway car, designed for closing off said pipe at the rear of a train, consisting of a shell formed with an internal cavity or chamber, two opposite openings thereinto for communication 80 with the opposite sections of said main pipe, a valve movable within said chamber, adapted to seat against and close either of said openings, said valve being shorter than the distance between said openings, whereby 85 when in an intermediate position both openings are uncovered, the said shell constructed with a free space or passage affording communication between said openings around the valve when in such intermediate position, 90 and formed with a branch opening for communication with the branch pipe leading to the radiators in the car, said branch opening communicating with said free space or passage, whereby when the valve is in said intermediate position it communicates with both the opposite main pipe openings, and when the valve is in either extreme position it communicates uninterruptedly with the opposite 95 or uncovered main pipe opening.

100 9. A valve for the main steam pipe of a railway car, consisting of a shell or chamber, having openings for communication with the respective sections of said pipe, combined with a sliding valve movable in guides or slide ways within said shell, an operating spindle passing through a stuffing box in said shell, an arm on said spindle within the shell entering a recess in the valve for communicating motion thereto, and a lever arm fixed on 110 said spindle exterior to the shell.

105 10. A valve for the main steam pipe of a railway car, consisting of the combination of a shell or chamber having openings for communication with the respective sections of said pipe, with a valve movable in said chamber adapted when in one position to close one 115 of the openings and when in another position to be unseated and afford free communication between said openings, an operating spindle passing through a stuffing box in said shell, and in mechanical connection within the shell with said valve, an operating handle in connection with said spindle exterior to the shell, and a locking device in connection 120 with said spindle for fastening it to hold the valve in either position.

11. A valve for the main steam pipe of a railway car, consisting of a shell or chamber having openings for communication with the 125 respective sections of said pipe, and extended beneath said openings to form a condensation 130

pocket or sediment well, a valve movable in said chamber adapted when in one position to close one of the openings and when in another position to be unseated and afford free communication between said openings, and an automatic trap or drainage valve for discharging condensed water from said shell, whereby in one interruption of the main pipe are combined the means for closing off the pipe at the rear of a train and for freeing

the steam in its passage through said pipe of condensed water.

In witness whereof I have hereunto signed my name in the presence of two subscribing witnesses.

EDWARD E. GOLD.
